[57] CLAIM

The ornamental design for a vacuum splint, as shown and described.

DESCRIPTION

FIG. 1 is a top plan view of a vacuum splint, showing my new design;

FIG. 2 is a top end elevation thereof;

FIG. 3 is a bottom end elevation thereof;

FIG. 4 is a cross-section taken on line 4—4 of FIG. 1;

FIG. 5 is a side elevation thereof; and

FIG. 6 is a cross-section taken on line 6—6 of FIG. 1.

The undisclosed opposite side of FIG. 1 is a mirror image of FIG. 1 with the omission of the nozzle.

FIG. 1FIG. 2FIG. 3FIG. 4FIG. 5FIG. 6
